MAINTENANCE IMPLEMENT FOR MANIPULATING WIRE AND HIGH VOLTAGE SWITCHES

Edward Walters, Keyport, N.J.

Application August 26, 1958, Serial No. 52,391

Term of patent 14 years

(Cl. D26—1)

Fig. 1 is a fragmentary front elevational view of a maintenance implement for manipulating wire and high voltage switches, showing my new design;

Fig. 2 is a fragmentary side elevational view; and

Fig. 3 is a front elevational view thereof, to a reduced scale.

The dominant features of my new design are shown in solid lines in the drawing, the broken line showing of supporting straps being omitted from Fig. 3 for convenience in illustration. A portion of the implement pole has been broken away in Figs. 1 and 2 for convenience in illustration.

I claim:

The ornamental design for a maintenance implement for manipulating wire and high voltage switches, as shown and described.
